Primary Examiner—Cynthia E Ramirez

(74) Attorney, Agent, or Firm—Brooks & Kushman P.C.

(57) **CLAIM**

The ornamental design for a pallet, as shown and described.

DESCRIPTION

FIG. 1 is a perspective view of the new design;
 FIG. 2 is a top plan view of the new design;
 FIG. 3 is a left side elevational view of the new design, the right side elevational view being a mirror image thereof;
 FIG. 4 is a front elevational view of the new design, the rear elevational view being a mirror image thereof; and,
 FIG. 5 is a bottom plan view of the new design.
